DUST COLLECTOR FOR PAPER MACHINES

Bror Karl Gustav Nystrom, Vaxajo, Sweden, assignor to
AB Svenska Flaktfabriken

Filed Aug. 19, 1975, Ser. No. 607,380

Term of patent 14 years

Int. Cl. D15—05

U.S. Cl. D49—11

FIG. 2

FIG. 1.

FIG. 3.

FIG. 4.

FIG. 1 is an end elevational view of a dust collector for paper machines in accordance with my design;
FIG. 2 is an opposite end elevational view thereof;
FIG. 3 is a top plan view thereof at a reduced scale;
FIG. 4 is a rear elevational view thereof;
FIG. 5 is a front elevational view thereof;
FIG. 6 is a bottom plan view thereof; and
FIG. 7 is a longitudinal partial sectional view thereof taken on line 7-7 of FIG. 3.

I claim:
The ornamental design for a dust collector for paper machines, substantially as shown and described.
